UNITED STATES PATENT OFFICE.

ROBERT MANN LOWNE, OF CATFORD, ENGLAND.

ELECTRICALLY-DRIVEN CLOCK AND OTHER ELECTRICALLY-DRIVEN RUNNING MECHANISM.

1,136,350.

Specification of Letters Patent. Patented Apr. 20, 1915.

Application filed November 18, 1911. Serial No. 680,977.

To all whom it may concern:

Be it known that I, ROBERT MANN LOWNE, subject of the King of Great Britain, residing at No. 108 Bromley road, Catford, in the county of Kent, England, have invented new and useful Improvements in Electrically-Driven Clocks and other Electrically-Driven Running Mechanisms, of which the following is a specification.

10 This invention relates to improvements in electrically driven clocks and other electrically driven running mechanisms.

15 The principal feature of the present invention resides in the means adopted for abstracting a portion of the mechanical energy, rendered available on the intermittent completion of an electric circuit through the winding of an electro-magnet, and employing such abstracted energy to 20 effect a repetition of the intermittent completion of the electric circuit, the remainder of the energy rendered available by the energizing of the electric circuit being employed in urging the hands of a clock, the 25 striking mechanism of a clock or other running mechanism.

30 Another important feature of this invention resides in the special means which are employed to silence the intermittent action 35 of the mechanism of an electric clock.

The means employed, in achieving the object first mentioned, comprise two insulated 40 rotating elements which are so mounted that portions thereof move approximately along the same circular path, one, called the "pursued" element, being caused to intermittently advance and separate itself from the other element called the "pursuer," the latter, by the effort rendered available on 45 effecting the separation being endowed with sufficient energy to enable it to continue the pursuit, the overtaking of the pursued element causing the energization of an electro-magnet and the forced displacement of the 50 armature thereof, thus providing the requisite energy to drive the running mechanism and reinstate sufficient energy in the pursuer to enable it to continue its pursuit and repeat the operation of drawing on the source of electrical energy to continue the performance.

Specific embodiments of this portion of the invention and also of the silencing devices will be described by reference to the accompanying drawing in which:—

55 Figure 1 shows diagrammatically a plan of construction embodying the first mentioned "driving" feature of this invention. Fig. 2 shows, in elevation, a portion of the mechanism of Fig. 1. Fig. 3 is a plan view, 60 showing an arrangement which is alternative to a portion of Fig. 1. Fig. 4 is a plan view of a portion of an electric clock which embodies the "silencing" features in addition to the "driving" device, Fig. 5 65 being a sectional elevation of the mechanism taken along the line 5—5 of Fig. 4.

70 Referring first to Figs. 1 and 2, A is the before-mentioned pursued element and B the pursuer. These two elements are co- 75 axially mounted, one on spindle *a* and the other on spindle *b* and are normally insulated from each other. The element A comprises a ratchet-wheel *a*¹ to which is secured a post carrying an electric terminal *a*² and on the opposite side of the axis of A an insulated push-piece *a*³. To the spindle of the pursuing element B an arm *b*¹ is secured which carries an electric terminal *b*² and a 80 spring *b*³ fixed to the arm at one end and adapted to be bent away from the arm at the other end. The element A is connected to the parts to be driven, as for example 85 the hands of a turret or other clock, the striking mechanism of a clock or other mechanism to which an urging force is required to be applied. The element B is, for most purposes, connected to a mechanism whereby it is constrained from an instantaneous overtaking of A, as for example by an escapement contrivance or by the vane device which controls the rate of movement of the striking mechanism of a 90 clock or alternatively by a fly-wheel. These mechanisms are not shown on the drawing. 95

For the purpose of operating the above described mechanism a source of electrical energy is provided, indicated by a battery *c*, an electro-magnet *d* and a pivoted armature *e*. This latter carries a pawl *e*¹ adapted to engage with the teeth of the before-mentioned ratchet-wheel *a*¹ and a spring *e*² 100

adapted to serve as a terminal or contact maker and breaker with a terminal f which is secured to the frame-plate of the machine. A spring g is also provided whereby the 5 armature is withdrawn from the poles of the electro-magnet, when the latter is de-energized.

The electric circuit, when complete, is along the lead h^1 , the winding of the electro-magnet, the lead h^2 , the spindle b , arm b^1 and when b^2 and a^2 are in contact, through the ratchet-wheel a^1 , its spindle a , the lead h^3 to the armature e and spring e^2 and, when the latter is in contact with 15 the terminal f , the circuit is completed back to the second pole of the battery c by the lead h^4 . When the circuit is thus closed the electro-magnet will be energized and attract the armature e . The consequent 20 angular displacement of e will, before it is completed, cause the separation of the spring e^2 from the terminal and break the circuit, permitting the spring g to withdraw the armature from the electro-magnet 25 and, through the medium of the pawl e^1 , force the ratchet-wheel a^1 through a small angle. In this manner an effort will be rendered available to drive the mechanism connected to A. In the resulting movement 30 of the ratchet-wheel the terminal b^2 will be left behind by the terminal a^2 and cause a gap in the electric circuit.

The angular displacement of the ratchet-wheel, relatively to the arm b^1 , will also cause the spring b^3 to be bent away from the arm by the push-piece a^3 . The push-piece a^3 will now serve as an abutment for the spring b^2 and enable it to apply a 35 rotative effort to the element B and cause its terminal b^2 to presently overtake the terminal a^2 and re-close the electric circuit and so repeat the performance.

I have found that the above described 45 operation is not absolutely dependent on the breaking of the circuit between e^2 and f , for the recoil of the armature, at the termination of its inward swing, will ordinarily cause the breaking of the circuit between b^2 and a^2 , but it will in general be 50 advantageous to provide the additional break in the electric circuit as described.

In Fig. 3, a device is shown whereby, 55 on the completion of the approach of the armature toward the electro-magnet, the circuit is positively broken between the pursued and pursuing elements, the urging force for driving the mechanism connected to the pursued element and the re-instatement in the pursuer of the necessary energy 60 to maintain the pursuit being derived during the spring-operated withdrawal of the armature as in Fig. 1. In Fig. 3 parts which correspond with Fig. 1 are similarly 65 lettered. The tail of the pivoted armature e carries a roller e^3 which on the approach

of the armature toward the electro-magnet engages with a lever k pivoted at k^0 and carrying a click k^1 which engages with the teeth of the ratchet-wheel a^1 in a manner similar to the engagement of the pawl e^1 70 which is carried by the armature. With such a mechanism, the approach of the armature toward the electro-magnet will cause the click k^1 to sufficiently advance the ratchet-wheel a^1 to separate the terminals 75 of the pursued and pursuing elements, thus insuring the return of the armature by the spring g , during which return the pawl e^1 will complete the advance of the ratchet-wheel and re-instate the energy in the spring 80 which is required to urge the pursuing element B.

Figs. 4 and 5 show the portions of an electrically-driven clock which are relevant to the present invention. These comprise, 85 with a modified form of construction of some details, the "driving" feature of this invention and combined therewith the silencing devices. The parts which correspond with those of Figs. 1 and 2 are similarly 90 lettered and the above description will to a considerable extent apply to the construction shown in Figs. 4 and 5.

Instead of the armature of the electro-magnet d being so pivoted as to approach 95 and recede from the electro-magnet in the direction of the axis of the magnet, the armature m is, in a known manner, secured to a spindle m^1 the axis of which is parallel to the axis of the electro-magnet, the armature being so constrained, when withdrawn by the spring n that its center line takes a position which is approximately at an angle of 45° with the line which joins the two poles of the electro-magnet d . 100

On the completion of the electric-circuit and energization of the electro-magnet, the armature will be angularly displaced by the magnetic force in the direction toward the line which joins the two poles of the magnet. In this movement an arm secured to the spindle m^1 and provided with a pin m^2 to which is connected the pawl o , is so angularly displaced as to withdraw the pawl 110 from the ratchet-wheel sufficiently to enable it to engage with the next tooth, the tension of the spring n , which is secured to the pawl, being thereby increased and serving, when the electric-circuit is broken, to return the armature to its normal position 115 and provide the force necessary to urge the ratchet-wheel and the mechanisms connected therewith, including the terminal a^2 and the push-piece a^3 which are carried on an arm a^4 secured to the spindle a of the pursued element. 120

The pursuing element comprises a balance-wheel escapement mechanism contained in the case p , shown in Fig. 5 but omitted from Fig. 4. This mechanism may be of 125

watch-like dimensions as its only duty is to rotate the arm b^1 of the pursuing element under the influence of the slight strain of the bent spring b^3 , and yet this feeble mechanism is able to invoke a considerable relay effort to drive a turret clock for example.

The breaking of the electric circuit, which corresponds to the action of the spring e^2 of Fig. 1, is effected as follows:—The extremity of a spring q carried by a post q^1 , insulated from the frame-plate r , is normally in contact with another spring s carried by the post s^1 which is in electrical connection with the frame-plate. When the electro-magnet is energized, a pin t , carried on an arm secured to the spindle m^1 of the armature, presses on the lower spring s and separates its extremity from that of the spring q and permits the armature to return to its normal position under the action of the spring n . The electric circuit from and to the battery c , when complete, is provided by the following sequence of elements:—The lead h^1 , winding of electro-magnet d , lead h^2 , case p , spindle b of pursuing element, arm b^1 , terminals b^2, a^2 when in contact, arm a^4 , frame-plate r , post s^1 , spring s , spring q , post q^1 and leads h^3 and h^4 . With such a construction, as above described, the only cause whereby an audible sound could be produced is that which occurs on the contact of the pawl o and the click u with the teeth of the ratchet-wheel. To eliminate or minimize sounds from such a cause, the extremities of the pawl and click are provided with cushioning springs. The pawl o may be formed with a bow o^1 permitting the extremity to yield relatively to the body of the pawl. Also, at the back of the extremity of the pawl, a spring o^2 is provided which deadens the contact of the pawl with the limiting abutment v on the completion of the spring-operated return swing of the armature. To prevent the pawl, on its withdrawal from the ratchet-wheel, from making a noisy contact with the succeeding tooth of the ratchet-wheel, another spring o^3 is interposed between the pawl o and the click u and this spring may be carried by the pawl as shown in the drawing or, alternatively, it may be carried by the click u or by the frame-plate, r . By the use of this spring, the pawl o will ride off one tooth of the ratchet-wheel into silent engagement with the next tooth. In order that the click u may drop from one tooth into silent engagement with the next, it also is furnished with a spring u^1, u^2 being a spring which maintains the click in contact with the ratchet-wheel.

In Fig. 4 is shown a disk w mounted on the spindle m^1 of the armature and frictionally connected thereto by a spring w^1 . By the aid of this device, abruptness in the movement of the armature is lessened with

advantage in respect to increased silence in the action of the mechanism.

I claim:

1. An intermittently-actuated electrically-driven mechanism comprising, in combination with a source of electricity, an electro-magnet, an electric-circuit which includes the winding of the magnet and a pivoted armature, contact carriers, a pursued and a pursuing electric-contact so secured to said carriers as to move in the same circular path, a spring mounted on the contact-carriers and so interposed between them as to urge the pursuing-contact, a time-expending device opposing the free advance of the pursuing-contact and means for advancing the pursued-contact by the displacement of the said armature; the arrangement being such that, when the pursued-contact is overtaken by the pursuer, pressure is exerted thereon in the direction of movement for a length of time only sufficient to energize the electro-magnet, the armature of which forthwith advances the pursued-contact and reinforces the energy in the spring carried therewith. 80

2. An intermittently-actuated electrically-driven mechanism comprising, in combination with a source of electricity, an electro-magnet, an electric-circuit which includes the winding of the magnet and a pivoted armature, contact carriers, a pursued and a pursuing electric-contact so secured to said carriers as to move in the same circular path, a spring mounted on the contact-carriers and so interposed between them as to urge the pursuing-contact, a time expending device opposing the free advance of the pursuing-contact, a second pair of contacts in the said circuit and means for advancing the pursued-contact by the displacement of the said armature; the arrangement being such that, when the pursued contact is overtaken by the pursuer, pressure is exerted thereon in the direction of movement for a length of time only sufficient to energize the electro-magnet, the armature of which separates the contacts of the said second pair, forthwith advances the pursued-contact and reinforces the energy in the spring carried therewith. 100

3. An intermittently-actuated electrically-driven mechanism comprising, in combination with a source of electricity, an electro-magnet, an electric-circuit which includes the winding of the magnet and a pivoted armature, contact carriers, a pursued and a pursuing electric-contact so secured to said carriers as to move in the same circular path, a spring mounted on the contact-carriers and so interposed between them as to urge the pursuing-contact, a time-expending device opposing the free advance of the pursuing-contact and a ratchet-wheel and spring-tipped pawl for silently advancing the pursued-contact by the displacement of the said 120 125 130

4
armature; the arrangement being such that, when the pursued-contact is overtaken by the pursuer, pressure is exerted thereon in the direction of movement for a length of 5 time only sufficient to energize the electromagnet, the armature of which forthwith advances the pursued-contact and reinforces the energy in the spring carried therewith.

In testimony whereof I have signed my name to this specification in the presence of 10 two subscribing witnesses.

ROBERT MANN LOWNE.
